UNITED STATES PATENT OFFICE.

ARCHIBALD S. McMILLAN, OF ST. LOUIS, MISSOURI, AND GEORGE W. WHIPPLE, OF CHERRYVALE, KANSAS.

PULVERIZED-COAL FEEDER.

Application filed October 21, 1921. Serial No. 509,358.

To all whom it may concern:

Be it known that we, ARCHIBALD S. McMILLAN and GEORGE W. WHIPPLE, citizens of the United States, and residents of St. Louis, Missouri, and Cherryvale, Kansas, respectively, have invented certain new and useful Improvements in Pulverized-Coal Feeders, of which the following is a specification.

This invention relates to improved apparatus for controlling the volume of coal fed to the burners of a furnace to control the intensity of the heat therein.

One object of the invention is to provide a structure whereby a jet of air or other pressure causes a quantity of fuel to be drawn through an orifice at a high velocity and fed to the burner. Another object is to provide novel means for controlling the volume of fuel fed to the furnace. A further object is to provide a slideable pipe which is adapted to convey pressure for feeding the fuel and also to control the area of the discharge outlet. Another object is to provide means for locking the feed nozzle in different positions of adjustment. A still further object is to combine and arrange the various elements so that they effectively perform their functions as set forth.

The invention will be understood from the following description and accompanying drawings in which

Fig. 1 is a side elevation showing one embodiment of the invention.

Fig. 1^a is a detail of parts shown in Fig. 1;

Fig. 2 is a view on an enlarged scale showing structural details;

Fig. 3 is a section on line 3—3 of Fig. 2;

Fig. 4 is a horizontal section on line 4—4 of Fig. 2.

Fig. 5 is a plan of parts shown in Fig. 1;

Fig. 6 is a section on line 6—6 of Fig. 5.

Referring to the drawings 5 is a collector from which the pulverized fuel is fed to a supply bin or hopper 6. To the bottom of the hopper is secured an angular rim 7 to one flange of which a casing 8 is fastened. This casing is formed with a plurality of chambers 9 which are in open communication at the top with the interior of the hopper 6. Bosses 10 are formed in the chambers 9 and are drilled to form conduits 11. In alignment with each conduit 11 a threaded opening is made for the re-

ception of the boss 12 of a frame 13 having upright end walls 14 and 15 and a bottom wall 16.

The wall 15 carries an integral boss 17 which is in alignment with and extends in the opposite direction to the boss 12. A pipe 18 is slidably mounted in the bosses 12 and 17 and suitable stuffing boxes 19 and 20 are provided to prevent leakage around said pipe. One end of the pipe is provided with a nozzle 21 of frustro-conical shape and formed with a central passage of restricted area. Secured to the pipe 18 at a point intermediate the stuffing boxes 19 and 20 is a split collar 22 having outwardly extending pins 23 formed thereon. These pins engage the walls of a slot 24 formed in a lever 25 which is pivoted at 26 to a bracket 27 secured to the underside of the frame 16. At its free end this lever is connected by means of a link 28, with a lever 29 pivoted at 30 to any suitable fixed support. At its upper end the lever 29 carries a pivoted hand grip 31 for operating a spring pressed latch-rod 32 which co-acts with the teeth 33 of a locking quadrant formed on one of the flanges of an angle iron 34 which is secured to the hopper 6. It is clear that as thus connected, movement of the lever 29 will reciprocate the rod 18 and cause a variation in the area of the orifice between the nozzle 21 and the conduit 11. By locking the lever 29 by means of the latch rod 32 it will be seen that the volume of material fed through the conduit 11 can be maintained to suit varying conditions.

Compressed air or other fluid pressure is supplied to the pipe 18 through a pipe 35 which is connected by means of fitting 37 to a Y-connection 38, one portion 39 of which is connected to a pipe 40 leading to burner 41 in the furnace F. The other branch 42 of the Y-fitting is connected by means of a pipe 43 and fittings 44 to a low pressure supply pipe 45 in which a substantially uniform pressure is maintained by means of a regulator 46 which controls the pressure of air supplied by the pipe 47 which pipe is connected to a suitable pump or blower, not shown. The casing 8 is formed with a plurality of chambers 9 and several of these chambers are connected as above described to control the supply of fuel to several of the larger burners 41 in the furnace. The furnace illustrated is of

the retort type such as used for the distillation of zinc and is also provided with a number of small upper burners 48 which are supplied with fuel fed from other chambers 9 of the casing. For controlling the volume of fuel supplied to the upper burners 48 we use the same arrangement as shown in Fig. 2 but connect the supply line to the burners in a slightly different manner as 10 will now be described.

The fittings 37^a and the Y-fitting are connected to the casing 8 in the same manner as above described and high pressure air is supplied to the branch 42^a of the fitting 15 38^a through a pipe 45^a which is connected to a suitable high pressure air supply. The outlet portion 49 of the fitting 38^a is connected to a riser 50 having an enlarged intermediate section 51 and a return bend 52 20 at the upper end thereof which enters the top of the hopper 6. Baffle elbows 53 are mounted within the enlarged section 51 and by means of pipes 54 are connected to the small burners 48, a valve 55 being provided 25 for each pipe 54 to control the flow of fuel to each burner 48.

In operation, when it is desired to supply fuel to the large burners 41, the lever 29 is 30 swung forward one or two notches from the position shown in Fig. 1 which will withdraw the nozzle 21 a short distance from the face of the boss 10 thereby forming an orifice between the walls of said nozzle and the conduit 11. The air pressure flowing 35 through the nozzle will create a strong suction which will draw the pulverized fuel from the hopper into the chamber 9 and through the restricted orifice around the nozzle and force the fuel through the fittings 37 and 38 to the pipe 40 where it will meet the auxiliary air supplied by the pipe 45 and will be carried 40 to the burners 41. The auxiliary air supply is of low pressure and assists the 45 furnace draft in gently feeding or "wafting" the fuel forward and also aids in promoting the combustion of the fuel in the furnace. The supply for the small upper burners 48 is controlled in substantially the 50 same manner as that above described except

that after the material flows through the Y-fitting 38^a it meets a blast of high pressure air which carries it upwardly through the riser 50 and a portion of the fuel is trapped by the baffle elbows 53 and flows on to the small upper burners 48, a certain portion of fuel and air being returned through the branch 52 to the top of the hopper.

The fuel which leaves the upper burners 60 48 enters the furnace at substantially the same low pressure as that which is admitted to the furnace by the lower burners 41.

As above mentioned the low pressure auxiliary air is controlled by the regulator 46. 65 This is set so that practically no pressure is exerted in the furnace chamber, the auxiliary air being supplied at such a low pressure that the draft on the furnace will not be materially affected thereby, and the cloud 70 of finely pulverized powdered fuel is assisted in its movement by the partial vacuum or draft of the furnace.

While we have described with great particularity the details of construction and 75 arrangement of parts of the embodiment of our invention illustrated, it is not to be interpreted that we are limited to such arrangements as various modifications and substitution of equivalents may be made 80 without departing from the spirit and scope of the invention as defined in the appended claim.

What we claim is:

The combination with a feed hopper and 85 a furnace of means below the hopper for creating a suction to withdraw pulverized fuel from the bottom of said hopper, a substantially horizontal feed nozzle movable longitudinally to control the volume of fuel 90 withdrawn by suction from the hopper and means for supplying an auxiliary stream of air at a pressure slightly greater than that of atmosphere to assist the furnace draft in drawing the fuel thereto and to promote 95 combustion.

In witness whereof, we have hereunto signed our names.

ARCHIBALD S. McMILLAN.
GEORGE W. WHIPPLE.
